THOMAS B. RIDER, OF LOS ANGELES, CALIFORNIA, ASSIGNOR, BY MESNE ASSIGNMENTS, OF ONE-HALF TO GEORGINA DE CASTRO-DANZIGER, NÉE McCLELLAN, OF LOS ANGELES, CALIFORNIA.

X-RAY TUBE.

1,287,598.

Specification of Letters Patent. Patented Dec. 10, 1918.

Application filed May 10, 1917. Serial No. 167,712.

To all whom it may concern:

Be it known that I, THOMAS B. RIDER, a citizen of the United States, residing at Los Angeles, in the county of Los Angeles and the State of California, have invented new and useful Improvements in X-Ray Tubes, of which the following is a specification.

My invention relates to improvements in X-ray tubes; and the objects of my improvements are, to regulate the focus between the cathode and the anode in an X-ray tube; to provide a cathode which will bring the focus slightly off the center on the anode; to provide an X-ray tube which allows a regulation of the focal distance while the X-ray tube is in use; to provide a cathode which allows the regulation of the focus so as to meet the anode in different points after the first met point has been ruined in the surface of the anode; the invention consisting in the construction, combination and arrangement of devices hereinafter more fully described and claimed, and illustrated in the accompanying drawing, in which—

25 The figure is an assembly of an X-ray tube with my device inserted.

Similar numbers refer to similar parts throughout the papers.

1 designates the glass globe of the X-ray tube, 2 designates an extension glass tube closed at the end 3 surrounding a steel tube 4. A wire 5 is fused into and through the closed end 3 outwardly forming one of the connections 6 for the electric circuit and inwardly connecting to the steel tube 4. An anode 7 is secured to the free end of the steel tube having preferably a tungsten disk 8 inserted into the surface. Another glass extension tube 9 serves as a holder for the auxiliary anode 10, which is connected to the connection of the main anode by the wire 11. A third extension end 12 is provided for the chemical vacuum regulator, a wire 13 being connected to the outside of the vacuum extension end and projecting toward the connecting end 14 of the cathode. The cathode wire 15 is fused into and through the glass extension tube 16 and secured to the cathode stem 17, which is 45 threaded on its free end 18. Turnably mounted on the threaded end of the cathode stem is the concave-faced cathode member 19. As will be seen in the drawing, the threaded bore 20 is eccentrically positioned

in relation to the concaved face 21 of the 55 cathode member 19, and, having the cathode made of material which can be influenced by a magnet, or having a piece 22 of suitable material secured to the side of the cathode, it will easily be understood that the cathode 60 can be operated from the outside by holding a magnet to the glass extension tube 16 near the cathode and then turn the whole X-ray tube, or move the magnet around the glass extension tube 16 in the direction in which 65 the cathode is wanted to turn, and, in thus turning the cathode on the eccentrically disposed bore, it will be understood that the focus can be directed toward different points on the surface of the anode. 70

Having the cathode threaded on the stem 17 serves also to lengthen or shorten the focal distance between the cathode 19 and the anode 7, as will also be easily understood.

It will furthermore be understood that 75 the cathode member 19 can be turned on the threaded end 18 of the stem 17 by shaking the X-ray tube, as the overweight formed by the eccentric position of the cathode member and the extra weight 80 formed on the cathode will cause the cathode to turn, the weighted side of the cathode keeping on the underside while the X-ray tube is shaken and simultaneously turned.

I am aware that X-ray tubes of various 85 constructions are known, but to lengthen the life of X-ray tubes and improve the devices by the several means described above, I claim:

1. In an X-ray tube a cathode having 90 turnable supporting means eccentrically disposed in relation to the focusing face.

2. In an X-ray tube a cathode having its supporting means eccentrically disposed in relation to the focusing face, and having a 95 weight-body provided on one side of the cathode of suitable material to be influenced by a magnet from the outside of the X-ray tube.

3. In an X-ray tube an anode projecting 100 into the X-ray tube from one side, a cathode stem projecting into the X-ray tube from the opposite side and threaded on its free end, and a cathode member eccentrically turnably mounted on the threaded end of 105 the stem for focusing the cathode toward different points in the surface of the anode.

4. In an X-ray tube an anode projecting

into the X-ray tube from one side, a cathode stem projecting into the X-ray tube from the opposite side, and a cathode member turnably mounted on the end of the stem 5 having a concaved face transverse to the stem, the center of the concaved face being eccentrically disposed to the center of the supporting stem.

5. In an X-ray tube an anode projecting into the X-ray tube from one side, a cathode stem projecting into the X-ray tube from the opposite side and threaded on its free end, a cathode member turnably mounted on the threaded end of the stem having a 10

concaved face toward the anode transverse to the stem, the center of the concaved face being eccentrically disposed in relation to the center of the supporting stem, and means formed on the cathode member for turning the cathode in the X-ray tube when so desired. 15

In testimony whereof I hereunto affix my signature in the presence of two witnesses.

THOMAS B. RIDER.
